UNITED STATES PATENT OFFICE

DUANE M. LILLIBRIDGE, OF ST. CHARLES, ILLINOIS

GLIDER

Application filed March 28, 1929. Serial No. 350,763.

The invention relates to improvements in gliders of the type in which an elongated seat is mounted upon a frame for forward and rearward movement, usually a swinging movement.

It is the object of the invention to provide unique means whereby, although the forward-to-rearward movement of the seat is not impeded, said seat is held against appreciable movement in an end-wise direction, so that there is no danger of the seat bumping upon the ends of the supporting frame or catching upon the seat suspenders.

With the foregoing in view, the invention resides in the novel subject matter herein-after described and claimed, description being accomplished by reference to the accompanying drawing.

Fig. 1 is a front elevation partly broken away and in section.

Fig. 2 is a top plan view.

Fig. 3 is a view similar to Fig. 1 but showing a different form of construction.

A main stationary frame is shown embodying two spaced vertical end frames 5 and a longitudinal bar 6 connecting the lower portions of said frames and suitably braced thereto as at 7. Above the bar 6 is a seat frame 8 suspended from the upper portions of the frames 5 by chains, rods or other desired means 9.

In Figs. 1 and 2, two contrivances C which I term equalizers, are shown connecting the frame 8 with the bar 6 to prevent endwise movement of the former. Any desired number of these contrivances may be used and as the two shown are of identical construction, only one will be described in detail.

The numeral 10 denotes a substantially vertical link which is pivotally hung from either the front or rear portion of the seat frame 8, and twin links 11 are disposed substantially in horizontal positions, are shown. These links 11 converge to a common point and at this point are pivoted at 12 to the lower end of the link 10. The widely spaced ends of the twin links 11 are pivoted at 13 to the bar 6. Preferably this bar is provided with two rigid L-shaped brackets 14 engaging the pivots 13. Similar brackets 15 are

employed at the upper end of the link 10 and contacting with opposite sides of the latter, said link 10 being connected with these brackets by a rivet or other pivot 16.

All of the link pivots 12-13-16 have their axes disposed longitudinally of the frame 8 and bar 6 so that they will not interfere with proper swinging of the seat. The links 10-11 are substantially rigid in a direction at right angles to the front-to-rear line of movement of the seat and hence they prevent this seat from moving endwise with any discomfort to the occupant or with danger of parts of the seat striking against the suspenders 9 or the end frames 5. Obviously, all front-to-rear and all vertical movements of the seat are permitted by the mounting of the links so that the latter may follow all movements of the seat except endwise movement thereof and will prevent the latter.

In Fig. 3, all construction is the same as that above described with the exception that each equalizer C embodies two downwardly converging vertical links 10^a instead of one vertical link such as 10. The upper ends of these links 10^a are pivoted at 16^a to brackets 15^a secured to the seat frame 8 and the lower ends of said links 10^a are pivoted at 12^a to the closely spaced front ends of the links 11. This provides a construction which is even more stable against endwise shifting.

Excellent results are obtainable from the details disclosed and they are therefore preferably followed. However, within the scope of the invention as claimed, variations may be made.

I claim:

1. In a glider, a stationary frame member, a seat member movable with respect thereto, twin links pivoted at spaced points to one of said members and converging to a common point, and another link pivoted to said twin links at said common point, said other link being pivoted also to the other of said members, the pivotal axes of the links being all transverse to the front-to-rear line of movement of the seat member, said links being substantially rigid in directions at right angles to said front-to-rear line to

prevent movement of the seat member transversely of this line.

2. In a glider, a stationary frame member, a seat member movable with respect thereto, twin links pivoted at spaced points to said frame member and converging to a common point, and twin links pivoted to said seat member at spaced points and also converging to a common point, the two sets of twin links being pivoted together at said common point.

3. A glider comprising two stationary end frames and a central horizontal bar connecting the lower portions thereof, suspenders hung from said end frames and a seat frame supported by said suspenders, twin links downwardly converging to a common point from said seat frame and pivoted at their upper ends to the latter, and additional substantially horizontal twin links converging to said common point and pivoted to said horizontal bar, the two sets of twin links being pivoted to each other at said common point.

25 In testimony whereof I have hereunto affixed my signature.

DUANE M. LILLIBRIDGE.
